UNITED STATES PATENT OFFICE

JOHANN JACOB KEYSER, OF AARAU, SWITZERLAND

SPINNING AND TWISTING MACHINE

Application filed January 28, 1928, Serial No. 250,259, and in Germany January 19, 1927.

This invention is concerned with spinning or twisting machines having a fixed or stationary ring rail. In the machines heretofore used either the cop was moved up and down on the spindle, or the spindle was raised and lowered in the cord drive casing. In any instance the cop or the spindle changed its position with relation to its bearing or support wherefrom a non-uniform running of the cop or spindle could result.

My present invention does away with this drawback. It consists in its broader aspect in that the spindles which are positively actuated by worm gear mechanisms are moved up and down with their actuating gears for the formation of the cops. This results in the advantage that the spindles are always in the same position with relation to their drive, so that the cops or spindles are always running uniformly and an unobjectionable yarn or cord is produced.

In the drawing which illustrates a preferred embodiment of my invention:

Fig. 1 is a vertical section through a double-side spinning machine taken along the line 1—1 of Fig. 3.

Fig. 2 is a fractional side view, looking towards the end of the machine.

Fig. 3 is a front view of a part of the machine.

Fig. 4 is a vertical sectional view of the control mechanism, looking towards the inside of the end wall of the machine.

Fig. 5 is a vertical section along line 5—5 of Fig. 4.

Fig. 6 is a plan view of the mechanism effecting the up and down movement of the spindle beam, looking from below.

Fig. 7 is a top view of the spindle nut adjusting mechanism.

The machine illustrated in the drawing as embodying my present invention belongs to the type of spinning machinery at which the spindles are positively operated by worm gears, as disclosed more in detail by my U. S. Patent No. 1,526,709.

As shown in the drawing this machine comprises the main bearing shield 1 and the standards 2 between which the spindle beam 3, the ring rail 4, the cord guiding beam 5

and the feeding and stretching mechanism are arranged. The spindle beam 3 is carrying the worm gear driven spindles 7 which are actuated by a common shaft 8 through the intermediary of worm gears 9. The spindle beam 3 is guided on dove-tailed guides 11 for upward and downward movement. In order that the cops may be formed the beam 3 is, in accordance with the shape of the cops, lifted and lowered by spindles 12 and besides lowered with relation to the ring rail 4 according to the growth of the cops, as will be readily understood by those skilled in this art.

The spindles 12 are rotatably carried in a beam 13 extending between the main bearing shield 1 and the standards 2 and are connected with worm gears 14 meshing with worms 15 of a lengthwise extending shaft 16, having support on both sides of the worms 15 in bearings 17.

The spindle beam 3 is provided with arms 18 each of which is rotatably carrying a nut 19 having a threaded engagement with the spindles 12, as shown, and being provided with worm gears 20 which mesh with worms 21 secured to a shaft 22. The shaft 22 is supported by bearings 23 and extends past the whole width of the machine. By the worms 21 engaging with the worm gears 20 the nuts 19 are normally locked against rotation. If therefore the spindles 12 are rotated they impart a lifting or lowering movement, as the case may be, to the spindle beam 3 by means of the nuts 19. By rotating also the nuts 19 an additional movement may be imparted to the beam 3.

In order that the spindle beam 3 in its totality may perform its lifting and lowering movement, I arrange, in accordance with one of the main features of this present invention, a special connection of its shaft 8 with the main actuating gear 24 of the machine. To this end the shaft 8 is provided with a worm gear 25 meshing with a long, vertically extending worm 26 carried by bearings 27 of the main bearing shield 1 of the machine. At the side opposite to worm gear 25 the worm 26 meshes with the main actuating gear 24 driven by a pinion 28 from the

non-illustrated motor. The extended worm 26 permits a vertical movement of the spindle beam 3 without disengaging gears 25 and 26.

In accordance with the usual practice of this type of machines the stretch and feed mechanism is actuated from the main gear 24, for example by means of an adjustable sprocket chain drive the shaft of the main gear actuating a sprocket wheel 29, which 10 drives a sprocket wheel 31 by means of a chain 30, sprocket wheel 31 being connected with a pinion 32 which meshes with an interchangeable pinion 33 actuating the stretch and feed mechanism.

15 The lifting and lowering movement of the spindle beam is preferably governed by the drive of the stretch and feed mechanism. To this end the main shaft 34 thereof which is actuated by pinion 33 is carrying a bevel gear 35 meshing with the bevel gear 36 of a vertical shaft 37 which at its upper end is supported in a bearing 38. The lower end of shaft 37 is loosely carrying two bevel gears 39 and 40 supported by bearings 41 20 and 42 respectively and engaging with a bevel gear 43 fixed to the shaft 16. Upon shaft 37 I arrange a coupling member adapted to rotate with the shaft and to be lengthwise shifted thereon and having jaws or 25 cones adapted to be engaged with corresponding jaws or cones of the gears 39 and 40 respectively so as to establish a positive drive between shafts 16 and 37 in the one or the other direction and effect the lifting or 30 lowering of beam 3, as will be readily understood.

The movement of the coupling elements so far described is preferably controlled by the drive of the bevel gears 39 and 40. To this 40 end the shaft 37 is provided with a worm 45 meshing with a worm gear 47 having nearly straight teeth and being carried by a stub shaft 46. The worm gear 47 is carrying an exchangeable cam disk 48 the cam 49 of which is acting on rollers 50 of a guide member 52 sliding in guides 51. The cam 49 is thus lifting and lowering the guide member 52 in accordance with the particular 45 number of revolutions of shaft 37, it being besides connected by a rod 53 with a lever 54 controlling the clutch element 44 by means of a pin 55.

55 Since also the additional vertical movement of the spindle beam 3 must be controlled by the machine, I further provide a pinion 56 meshing with gear 47 but having only half the number of teeth thereof. The pinion 56 is revolving on a stub shaft 57 of the main bearing shield 1 and carries an eccentric pin 58 projecting into the longitudinal slot 59 of a lever 61 journalled at 60 at its upper end and being pivoted at its lower end to an arm 62, the other end of which is pivoted to a lever 63. The lever 63 is pivoted 60 to the shaft 22 which moves upwardly 65

and downwardly with the spindle beam and carries a feed pawl 64 cooperating with a ratchet 65 mounted on the shaft 22. At each stroke of the spindle beam the ratchet 65 is rotated a certain amount by the pawl 64, immediately before the clutch 44 is reversed. Since the shaft 22 has a relatively limited vertical movement, its displacement is without substantial influence on the connecting link 62. 70 75

I claim:

1. In a spinning machine, a ring rail, a spindle beam mounted for movement toward and from the ring rail, spindles rotatably mounted on the spindle beam, a shaft for imparting motion to the spindles and movable with the spindle beam, a drive shaft, gearing interposed between the drive shaft and the spindle rotating shaft for rotating the last mentioned shaft, and means actuated by an element of the gearing for imparting movement to the spindle beam in synchronism with the formation of the cops on the spindles. 80 85

2. In a spinning machine, a ring rail, a spindle beam mounted for movement toward and from the ring rail, spindles rotatably mounted on the spindle beam, a shaft for imparting rotary motion to the spindles and movable with the spindle beam, a drive shaft, gearing interposed between the drive shaft and the spindle rotating the last mentioned shaft, and means actuated by an element of the gearing for imparting movement to the spindle beam in synchronism with the formation of the cops on the spindles, the said means comprising a worm in mesh with a corresponding element of the gearing, and a worm gear upon the spindle rotating shaft in mesh with the worm. 90 95 100

3. In a spinning machine, in combination, a stretch and feed drive for the yarn to be spun including a main driving shaft, a ring rail, a spindle beam mounted for movement toward and from the ring rail, spindles rotatably mounted on the spindle beam, a shaft for imparting rotary motion to the spindles and movable with the spindle beam, a drive shaft, gearing interposed between the drive shaft and the spindle rotating shaft for rotating the last mentioned shaft, the said gearing comprising a worm, a shaft intermediate the main drive shaft and the worm, a gear upon the said main drive shaft, a gear upon the said intermediate meshing with the gear upon the main drive shaft and with the worm, a worm pinion upon the spindle rotating shaft meshing with said worm, means for imparting movement to the spindle beam toward and from the ring rail comprising a worm shaft, beams interposed between the worm shaft and the main shaft of the stretch and the feed drive for rotating said worm shaft, threaded spindles mounted for rotation, threaded rotary elements movable with 105 110 115 120 125 130

the spindle beam and engaging said spindles, and worm gears upon the threaded spindles having threaded engagements therewith and meshing with the worm shaft.

4. In a spinning and twisting machine, a stationary ring rail, a spindle carrying beam having spindle actuating worm gears, and a common actuating worm shaft therefor, means for vertically reciprocating the said beam and the spindles carried thereby at a constant reciprocating stroke with relation to the stationary ring rail and while the spindles continue to rotate, and means for imparting to the said beam an additional downward movement with relation to the stationary ring rail at the ends of its reciprocations.

In testimony whereof I affix my signature.
JOHANN JACOB KEYSER.
